UNITED STATES PATENT OFFICE.

HARTLEY O. BAKER, OF PUEBLO, COLORADO, ASSIGNOR TO THE BAKER STEAM MOTOR CAR AND MANUFACTURING CO., INC., OF PUEBLO, COLORADO.

ENGINE-FRAME.

1,336,715.

Specification of Letters Patent. Patented Apr. 13, 1920.

Application filed June 19, 1918. Serial No. 240,827.

To all whom it may concern:

Be it known that I, HARTLEY O. BAKER, a citizen of the United States, residing at Pueblo, in the county of Pueblo and State 5 of Colorado, have invented certain new and useful Improvements in Engine - Frames; and I do hereby declare the following to be a full, clear, and exact description of the invention, such as will enable others skilled 10 in the art to which it appertains to make and use the same.

This invention relates to engines, and more particularly to fluid expansion engines, the principal object of the invention 15 being to improve and simplify the details of construction thereof.

Another object of the invention is to provide an engine of the above stated character adapted to be attached to a standard rear 20 axle housing and embodying means for supporting the differential unit within said axle housing.

With these and other objects in view as will appear as the description proceeds, the 25 invention comprises the various novel features of construction, combination and arrangement of parts as will be fully described hereinafter and afterward specifically claimed.

In order that the construction and operation of the invention may be readily comprehended by those skilled in the art to which the invention relates, I have illustrated an approved embodiment of my invention in the accompanying drawings, in which—

Figure 1 represents a sectional plan view through a fluid expansion engine of the slide valve type connected up to a standard 40 rear axle housing.

Fig. 2 represents a vertical longitudinal sectional view taken on a plane indicated by the line 2—2 on Fig. 1.

Fig. 3 represents a transverse sectional 45 view taken on a plane indicated by the line 3—3 on Fig. 1.

Fig. 4 represents a transverse sectional view taken on a plane indicated by the line 4—4 on Fig. 1.

Fig. 5 represents a similar view taken on 50 a plane indicated by the line 5—5 on Fig. 1.

Fig. 6 represents a side elevation of one of the main engine frame members.

Fig. 7 represents a top plan view thereof.

Fig. 8 represents a bottom plan view of 55 the engine casing.

Fig. 9 represents a side elevation of the casing.

Fig. 10 represents a top plan view of the casing. 60

Fig. 11 represents a longitudinal sectional view taken on a plane indicated by the line 11—11 on Fig. 10, and

Fig. 12 represents a horizontal sectional view taken on a plane indicated by the line 12—12 on Fig. 9.

Similar characters of reference are used to denote like parts throughout the accompanying drawings.

Referring more particularly to the drawings, 1, 1 indicate a pair of steam cylinders between which is positioned a slide valve chest 2 having arranged therein a pair of slide valves 3, all of said parts being of the usual construction in engines of this type. 75 One end of each cylinder is closed by a head plate 4, while the opposite ends of said cylinders are closed by a single head plate 5.

6 is an auxiliary head plate spaced from the head plate 5. 7 indicate the usual pistons and 8 the piston rods which are slidably mounted through the head plates 5 and 6 and integral bearing sleeves 9 carried by said head plates.

Each of the slide valves 3 is fixed to a 85 valve rod 10 also slidably mounted through the head plates 5 and 6 and in integral bearing sleeves 11 carried by these head plates. An oil pan 12 is connected between the head plates 5 and 6 concentrically of 90 each of the piston rods 8, as clearly shown in Figs. 1 and 5, to receive a quantity of oil to lubricate the piston rod 8.

The main engine frame comprises a pair of side frames, each of which embodies upper and lower bars 13 and 14 connected at their rear ends by a part 15, while their forward ends are bent laterally to provide attaching flanges 16 which are secured to the auxiliary head plate 6 by bolts 17. The 95 rear portion of each side frame is cut away, as at 18, and reinforced at this point by webs 19 extending downwardly and outwardly to an attaching flange 20. 21 indicates a semicircular flange adjacent the rear portion of the frame and carries a similar shoulder 22. A hanger projects from the rear end of the frame and embodies 100 105 a

bracket 23 and a strap 24 detachably connected to the latter by bolts 25.

These side frames are arranged in spaced relation to each other so that the flanges 21 5 and the shoulders 22 will coöperate to provide a flanged ring adapted to be connected to a standard rear axle housing 26 by bolts 27, so that the hangers will project into the housing to support the differential unit 28 10 in operative position. 29 are the usual or standard rear axles which project through adjustable collars 30 into the differential unit. These collars are threaded into the hangers and are adapted to be adjusted 15 against the hubs 31 of the differential unit to adjust the driving gear 32 thereof laterally, said collars being held in adjusted position through the medium of locking keys 33 carried by the hangers. 34 indicates the usual cover plate on the axle housing 20 which can be removed in order to take out the differential unit from the rear.

The main engine crank shaft 35 is mounted in suitable bearings 36 in the side frames 25 and held in place by bearing straps 37. Cranks 38 are fixed to the opposite ends of the crank shaft and are connected to the cross heads 39 carried by the piston rods 8 by connecting rods 40.

30 Each cross head consists of a hollow tapered block, as clearly shown in Figs. 2 and 4, within which the forward end of each connecting rod 40 is pivoted by a pin 41. 42 indicates a transverse opening in the head 35 block for access to the clamping nut 43 on the rear end of the piston rod 8. The upper and lower edges of the cross head block are provided with tongues 44 to slidably fit within the grooves 45 of cross head shoes 46 40 adjustably mounted on the cross head block by screws 47 threaded through the angular ends 48 of the shoes and into the head portion of the cross head block. The outer surfaces of the shoes 46 are convexed to 45 slide within the concaved wear plates 49 carried by the cross head guides or brackets 50 supported by the arms 13 and 14 of the side frame.

Locking screws 51 extend through the 50 cross head block into engagement with the shoes 46 and serve to hold the shoes in adjusted position. By this construction as just described, it will be apparent that any wear between the cross head proper and its 55 respective guides can be taken up by the adjustment of the shoes 46.

The valve gearing embodying means for reversing the position of the valves with respect to the piston stroke is operatively 60 associated with the main driving gear 52 fixed on the crank shaft 35 and provided with an internal gear 53. A pinion 54 meshes with the internal gear 53 and is supported by the shorter arm 55 of a yoke 65 56, said yoke being provided with a longer

arm 57 rotatably mounted on the crank shaft, as clearly shown in Fig. 3. The main gear 52 meshes with the differential driving gear 32 so that the power from the engine may be transmitted directly to the rear 70 axles. A gear sleeve 58 is loosely mounted on a crank shaft and meshes with the pinion 54 and with a gear 59 mounted on a stub shaft journaled in bearings 60. Eccentrics 61 are fixed to opposite sides of the gear 59 75 and are connected to the valve rods 10 by rods 62.

A tubular casing 63 is positioned around the engine structure and has one end resting upon and bolted to the shoulder 64 on 80 the rear face of the head plate 5, while its other end is slightly reduced to fit the annular shoulders 22 of the engine frames, said end being bolted to the shoulders to form an oil-tight joint. The opposite sides 85 of the casing are provided with openings 65 which are covered by plates 66, said plates being each provided circumferentially with a rib 67 to fit a corresponding groove in the casing. These plates are clamped in 90 position by a set-screw 68 passing through a pivotal bar 69, the ends of which are adapted to lockingly engage behind lugs 70. The opposite sides of the casing are also provided adjacent the forward end with 95 hand-holds 71 covered by plates 72 bolted to the casing, whereby access may be had to the oil pans 12 in order to refill them when necessary.

An opening 73 is formed in the top of 100 the casing and covered by a plate 74 bolted to the casing. As shown in Fig. 2, the upper end of the yoke 56 projects up through the casing and into a housing 75 through one end of which is slidably mounted the gear 105 shifter rod 76, said rod being pivotally connected to the yoke 56. The casing is also provided in its top adjacent the forward end with an opening 77 covered by a slide plate 78 adapted to have one edge slid under 110 a pair of lugs 79 and its opposite edge secured to the casing by a thumb screw 80.

By constructing the various parts of the engine as hereinbefore described, it will be apparent that the same can be quickly and 115 readily assembled and disassembled and that means is provided for supporting the differential unit within the rear axle housing by the main engine frame. By disconnecting the engine from the rear axle housing by 120 removing the bolts 27, the engine and the differential unit, after the axles 29 have been removed, can be removed from the rear axle housing as a single unit without the necessity of having to remove the rear cover 125 plate 34 and taking the differential out separately as is the case with the ordinary construction now in use.

Since the operation of this engine with the exception of the reversing valve gear is 130

the same as all engines of this type, it is not thought necessary to enter into a detailed description of its operation. It may be stated that the valve reversing gear may be actuated by the rod 76 to reverse the position of the slide valves 3 with respect to the pistons 7 so that the engine can be reversed. However, this reversing valve gear forms the subject-matter of a separate application 10 in which the details of construction and operation have been clearly set forth.

While I have described the general details of construction and arrangement of the various parts of the engine, I desire to have 15 it understood that such changes in construction and arrangement of parts may be made, when desired, as come within the scope of the appended claims.

What I claim is:—

20 1. An automobile propulsion mechanism embodying a rear axle housing, engine cylinders having a head plate, a frame rigidly connected at one end to said head plate and extending to the axle housing, a crank shaft 25 mounted in said frame, and a casing inclosing said frame and connected at one end to said head plate, said frame having supporting means adjacent to the axle housing to which the other end of the casing is fitted 30 and secured, and the frame having an out-

standing flange projecting beyond said supporting means and the end of the casing and secured to the axle housing.

2. An automobile propulsion mechanism embodying a rear axle housing, rear axles 35 therein, a differential gearing between the axles, engine cylinders having a head plate, a frame rigidly connected at one end to said head plate and extending to said axle housing, said frame being provided with an 40 outstanding flange rigidly secured to the axle housing, said frame having a shoulder adjacent to the flange, and brackets extending beyond the flange into the axle housing and embracing the axles, a crank shaft 45 mounted in said frame and connected with said differential gearing, and a casing inclosing the frame and connected at one end to said head plate and secured at its other end on said shoulder, said frame and casing 50 fitting together at points along their lengths to brace one another.

In testimony whereof I have signed my name to this specification in the presence of two subscribing witnesses.

HARTLEY O. BAKER.
